UNITED STATES PATENT OFFICE

2,596,495

METHOD OF MANUFACTURING PRE-STRESSED CONCRETE STRUCTURAL MEMBERS

Stelio Macerata, Johannesburg, Transvaal,
Union of South Africa

Application December 31, 1947, Serial No. 795,003
In Great Britain January 10, 1947

1 Claim. (Cl. 72—0.5)

2

This invention relates to the manufacture of structural members. More particularly, but not exclusively, this invention relates to girders, tension and compression members suitable for use in lattice girders, masts, and to columns.

A structural member according to this invention comprises a metal or other tube surrounding a core of cementitious material, which is reinforced by pretensioned reinforcing wires or rods and is maintained in a state of compression within said tube even when said member is not exposed to any external load.

When the structural member is of substantial length, it may comprise a plurality of tubes, each two adjoining tube ends having interposed between them a member which provides an inlet for grout or mortar, and which is arranged to have passed therethrough the rods or wires. Such intermediate member may provide part of a strut or brace.

The invention also comprises a compound structure which comprises at least two structural members of the kind specified in either of the last two preceding paragraphs.

In accordance with the invention, a method of producing a structural member of the aforementioned type comprises the steps of providing a tube; closing the ends of the tube with closure members each of which is formed with a spigot which is seated in its respective tube end as in a socket; providing metal rods or wires extending axially through the whole length of said tube; anchoring the rods or wires to one of said closure members and allowing the opposite ends of said rods or wires to project through the other member; attaching said opposite ends of the rods or wires to a tensioning device which acts on the closure member through which the rod or wire ends project without being anchored thereto so as to tend to draw the closure members relatively towards one another when tension is applied to the rods or wires; filling the tube with an aggregate; tensioning the rods or wires by means of the tensioning device; forcing cementitious material into the tube under pressure to fill the interstices in the aggregate; and allowing the cementitious material to set.

If desired, the steps of tensioning the rods or wires and forcing cementitious material into the tube may be repeated alternately until the rods or wires are pretensioned to the required degree and the cementitious material and aggregate stressed to the required degree of compression.

To facilitate complete filling of the interstices with grout or mortar and to obtain a good dis-

tribution of pressure within the tube, vibration may be resorted to while the cement or mortar is being forced into the tube.

When the structural member is of substantial length and comprises a plurality of tubes, each two adjoining tube ends have interposed between them a member which provides an inlet for the grout or mortar and which is arranged to have passed therethrough the rods or wires.

10 In a modification of the process of the invention, the rods or wires are from the start pre-stressed to the desired degree, and the tube (or the compound tube comprising at least two tubes and at least one member interposed between the adjacent ends of the two tubes) filled with aggregate, grout or cement mortar being thereafter forced in under pressure.

The invention will be further described with reference to the accompanying drawings, in

20 which:

Figure 1 is a section of a structural member in the course of its manufacture.

Figure 2 is a section II—II of Figure 1.

With reference to the figures, 1 and 2 indicate co-axially mounted tubular sections which may be made of metal, concrete or other suitable material. Such tubular sections are sufficiently strong to resist the radial pressure which will be imposed on them as hereinafter described. 30 The end 3 of the section 1 is closed by a member 4 which provides a spigot 5 which is seated in the end 3 as in a socket. Similarly, the end 6 of the section 2 is closed by a member 7 providing a spigot 8 which is seated in the end 6.

35 Interposed between the respective ends 9 and 10 of the sections 1 and 2 is a member 11 which provides an inlet conduit 12 through which cementitious material may be forced into the interior of the tubular sections 1 and 2. Rubber gaskets 13 which are held in place by clamps 14 are used to insure a tight connection between the sections 1 and 2 and the members 4, 7 and 11.

40 15 are reinforcing rods or wires which are anchored in the members 7 as by a cross-piece 45 16 and the free ends 17 of such rods or wires project through holes 18 in the member 4. Said free ends 17 further pass through a clamp 19 which is seated on the member 4, and are connected to a suitable tensioning device, e. g. to 50 one of the movable parts of a hydraulic jack (not shown), the other movable part of which is arranged to rest on and to act upon the clamp 19. The rods or wires 15 also pass through holes 55 21 in the member 11. The size of the holes 18 and 21 relative to that of the rods or wires

15 is such that when tension is applied to the rods or wires, they are just free to move relative to the members 4 and 11.

In accordance with the method of the invention, the tubular sections 1 and 2 are first of all filled with aggregate. This may conveniently be done when the sections are being assembled to the members 4, 7 and 11. The rods or wires 15 are slightly tensioned and thereafter grout or cement mortar is forced into the sections through the inlet conduit 12, until they are completely filled (as may be shown by a tendency for the grout or mortar to be pressed out of the sections at the joints of the latter with the members 4 and 7). Thereupon, tension of the rods or wires is increased and additional grout or mortar is forced into the tubular sections, and the steps of increasing the tension of the rods or wires and of forcing additional grout or mortar into the sections are repeated until the rods or wires are tensioned to the required degree of pre-stressing and the core stressed to the required degree of compression. The cementitious material is then allowed to set.

When grout or cement mortar is, as aforementioned, forced into the tubular sections, the pressure will tend to move the end closure members 4 and 7 outwards relative to the sections after the free space of the latter has been completely filled, and at least traces of the grout or mortar will accordingly show at the ends 3 and 6 of the respective sections 1 and 2. When, thereafter, the tension on the rods or wires 15 is further increased by pulling directly on them (the grout or mortar inlet 12 being blocked against return flow), the increased tension and reaction on the closure members 4 and 7 will tend to force the latter to return to their original positions. At the same time the pressure of the core is increased.

The repetition of the steps of tensioning the rods or wires and forcing grout or mortar into the sections is necessary in order to settle the material down and produce a homogeneous compacted core. From a practical point of view, satisfactory compaction of the core is not otherwise achieved.

After the cementitious material has set, the tensioning means is removed. With relatively long multi-section structures, the clamps may also be removed, but if the structures are short, they are preferably left in place. The projecting ends of the rods or wires 15 are cut off, if desired, and the structural member is ready for use.

Due to the pre-stressing of the cementitious core, the tube 1 is normally tensioned and if an axial direct load is applied to a structural member of the aforesaid kind, the said core becomes further compressed and, as a result, the tension in the tube 1 tends to increase.

Such lateral restraint brings about an increase in bond between the material of said cementitious

core 23 and the reinforcing rods or wires 15 embedded therein and at the same time an increase in the ultimate compressive strength of the cementitious core and, accordingly, of the structural member of this invention.

I claim:

A method of forming an extended structural member originally consisting of a plurality of tubular sections and each respectively provided with a filling conduit, and having end closures with a plurality of tensioning rods extending longitudinally through the inside hollow passages of the tubular sections and through the end closures so that said rods may be accessible for tensioning by means external of the structural member, to tightly press the end closures against the structural member, said method consisting of filling the tubular sections with aggregate while they are being assembled end to end; connecting and sealing juxtaposed ends of the respective adjacent sections to permit free passage of cementitious material and to seal those ends to limit leakage of the cementitious material; similarly closing and sealing the outer ends of the extended member at the end closures to limit leakage; tensioning the several rods; forcing cementitious material under compression into the tubular sections through the conduits until the compression of the filling material exhibits oozing at the sealed regions; re-tensioning the several tension rods to further compress the filling material; additionally packing more cementitious material into the structural member until oozing is again manifested; and repeating such further tensioning of the tension rods and pressure filling of the structural member with cementitious material until the compression value of the filling material attains a predetermined value; and then allowing the cementitious material to set.

STELIO MACERATA.
